UNITED STATES PATENT OFFICE.

JAMES B. STANLEY AND JAMES H. CLOYES, OF DES MOINES, IOWA, ASSIGNEES
TO THE DES MOINES BUGGY COMPANY, OF SAME PLACE.

RUNNING-GEAR.

SPECIFICATION forming part of Letters Patent No. 425,891, dated April 8, 1890.

Application filed January 3, 1890. Serial No. 335,815. (No model.)

To all whom it may concern:

Be it known that we, JAMES B. STANLEY and JAMES H. CLOYES, citizens of the United States of America, and residents of Des Moines, in the county of Polk and State of Iowa, have invented an Improved Running-Gear for Vehicles, of which the following is a specification.

Heretofore side springs have been fixed to a bolster on the front axle and the hind axle, and reaches having lateral bends fixed to the same bolster and axle and the central portions of the springs, and then connected at their centers by cross-bars in such a manner that a box or body could be fixed on the cross-bars at its central portion to project backward and forward in a plane above the axles.

Our invention consists in the construction and combination of a two-part reach with side springs, a bolster, and an axle, as hereinbefore set forth, in such a manner that the two parts of the reach will reciprocally reinforce each other, serve as auxiliary springs in supporting and distributing weight, brace the side springs, and also serve as cross-bars to support a box or body.

In the accompanying drawings, Figure 1 is a perspective view of the front part and Fig. 2 of the rear part of the reach. Fig. 3 is a bottom view of the running-gear, showing the relative positions of the two parts of the reach to each other, the side springs, and the front and rear axles. Fig. 4 shows the same elements combined, but the form of the reach modified. Fig. 5 is a side view showing a box upon the springs and reach, as required for practical use.

A is the front axle, B the rear axle, and C a bolster on the front axle.

D are mating leaf-springs in parallel position, fixed to the bolster at their front ends and to the rear axle at their back ends by means of clips and screw-bolts, or in any suitable way.

F is the front portion of our two-part reach, preferably made of a flat bar of steel and triangular in shape. Its front end is connected with the center of the front axle by means of a clip or bolts, or in any suitable way, and is perforated to admit the passage of a pivotal king-bolt that extends through the bolster,

and is the center of motion of the axle, connected with the bolster by means of the fifth-wheel of common form. The sides of the rear portion of the triangular-shaped part of the reach extend under the central portions of the side springs.

G is the rear portion of the reach, made of the same material and preferably U-shaped. Its closed front end corresponds in width with the rear end of the part F, so that the rear end of the one part and the front end of the other will overlap each other at their sides, to be jointly fixed to the centers of the side springs D by means of clips or bolts to produce a complete reach that will have vertical flexion and motion in concert with the side springs, but will, in combination with the springs, produce a rigid frame that will resist lateral pressure and torsional strain.

In place of making the overlapping ends of the two parts of the reach straight, they may be curved, as indicated by dotted lines in Fig. 4, to widen the base upon which the box or body H is fixed by means of bolts in a common way.

We are aware U-shaped frames have been fixed to an axle and direct to side springs; but our manner of producing a rigid reach by overlapping the mating ends of two rigid frames and fixing them jointly to side springs is novel and greatly advantageous in the construction and use of a running-gear.

We claim as our invention—

1. A reach for vehicles, composed of a triangular-shaped frame adapted to be fixed to the center of the front axle and to the centers of two parallel side springs, and a U-shaped frame adapted to have its ends fixed to the end portions of the rear axle and its central portion to the same springs and at the same point where the triangular-shaped frame is attached to the springs, and to overlap the rear portion of the triangular frame, for the purposes stated.

2. The triangular-shaped frame F and the U-shaped spring G, in overlapping position with each other and in combination with the front axle of a vehicle, the rear axle, and two side springs, substantially as shown and described, for the purposes stated.

3. An improved running-gear for vehicles,

composed of two axles of uniform length, a
bolster pivoted to the front axle, two side
springs fixed to the end portions of the rear
axle and the end portions of the bolster on
5 the front axle, a frame fixed to the center of
the front axle and the central portions of the
two side springs, and a frame fixed to the
end portions of the rear axle, and also fixed
to the same springs at the same point, so the

two frames will be in an overlapping position 10
at the points where they are jointly fixed to
the springs, for the purposes stated.

JAMES B. STANLEY.
JAMES H. CLOYES.
